DESCRIPTION

The sole FIGURE is a front view of the “credit card with V-shaped number layout” showing my new design. The broken line is included to show portions of the claimed design and forms no part of the claimed design.

1 Claim, 1 Drawing Sheet

CREDIT CARD

A 2D pixel art scene featuring a central five-pointed star surrounded by a dashed circle of smaller stars, with various symbols (locks, question marks, and question mark blocks) scattered around the perimeter.
